(57) **CLAIM**

The ornamental design for a recreational vehicle, as shown and described.

DESCRIPTION

FIG. 1 is a front perspective view of a recreational vehicle in accordance with the present invention;

FIG. 2 is a rear perspective view of the recreational vehicle in FIG. 1;

FIG. 3 is a left side elevation view of the recreational vehicle in FIGS. 1 and 2;

FIG. 4 is a right side elevation view of the recreational vehicle in FIGS. 1-3;

FIG. 5 is a top plan view of the recreational vehicle in FIGS. 1-4;

FIG. 6 is a front elevation view of the recreational vehicle in FIGS. 1-5;

FIG. 7 is a rear elevation view of the recreational vehicle in FIGS. 1-6;

FIG. 8 is a front perspective view of the recreational vehicle in FIGS. 1-7 with the roof portion and rear portion in an open position;

FIG. 9 is a rear perspective view of the recreational vehicle in FIG. 8;

FIG. 10 is a left side elevation view of the recreational vehicle in FIGS. 8-9;

FIG. 11 is a right side elevation view of the recreational vehicle in FIGS. 8-10;

FIG. 12 is a top plan view of the recreational vehicle in FIGS. 8-11;

FIG. 13 is a front elevation view of the recreational vehicle in FIGS. 8-12; and,

FIG. 14 is a rear elevation view of the recreational vehicle in FIGS. 8-13.

The broken lines in the drawings illustrate portions of the recreational vehicle that form no part of the claimed design.
